Primary Examiner — Rosemary K Tarcza*Assistant Examiner* — Seth David Kumpf(74) *Attorney, Agent, or Firm* — LAW OFFICES OF MICHAEL L. WISE, LLC(57) **CLAIM**

The ornamental design for a faceplate, as shown and described.

DESCRIPTION

FIG. 1 is a front perspective view of a faceplate in accordance with my new design;

FIG. 2 is a front side view thereof;

FIG. 3 is a left side view thereof;

FIG. 4 is a right side view thereof;

FIG. 5 is a rear side view thereof;

FIG. 6 is a top side view thereof; and,

FIG. 7 is a bottom side view thereof.

The dot-dot-dash broken lines define the bounds of the claimed design and form no part thereof.

The faceplate is shown with a symbolic break in its width.

The appearance of any portion of the article between the break lines forms no part of the claimed design.
